UNITED STATES PATENT OFFICE.

THOMAS H. BLAIR, OF BOSTON, MASSACHUSETTS.

TRIPOD-TOP FOR PHOTOGRAPHIC CAMERAS.

SPECIFICATION forming part of Letters Patent No. 364,629, dated June 14, 1887.

Application filed January 22, 1887. Serial No. 225,146. (No model.)

To all whom it may concern:

Be it known that I, THOMAS H. BLAIR, a citizen of the United States, residing at Boston, in the county of Suffolk and State of Massachusetts, have invented certain new and useful Improvements in Tripod-Tops for Photographic Cameras; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to tripod-tops for photographic cameras; and it consists in the improved shape and construction of said tops, whereby the entire apparatus is rendered more steady and free from vibrations, especially in outdoor work. This effect is produced by moving the pivotal point of attachment of one of the legs of the tripod-top outwardly or away from the bolt by which the camera-box is secured.

Figure 1 of the drawings represents a perspective view; Fig. 2, a horizontal central section. Fig. 3 is an elevation with the tripod complete and set up.

Hitherto, in the manufacture and construction of tripod-tops for photographic cameras, they have been made triangular in general shape, while the legs of the tripod have all been disposed at the same fixed distance from the center of said tripod. The latter is at this point provided with a bolt or pin upon which the camera-box secured thereto is pivoted.

It is evident that when the camera-box is mounted upon its tripod, and with the bellows extended for focusing purposes, there is no support beneath and in the rear for this now projecting part of the camera-box. The latter now tends to tip back, and in outdoor work vibrations and unsteadiness of the camera-box are increased.

My invention has for its object such a change in the construction and shape of the tripod-top that the rear portion of the camera-box, whether the bellows are extended or not, shall be furnished with a firm and stable support; and hence I have made one of the tripod-legs adjustable upon the tripod-top; consequently, by

moving the pivotal point of attachment of such leg outwardly upon the tripod-top, the size of the latter is practically increased and stability of the entire apparatus produced.

To this end I have shown at A a tripod-top cut preferably from wood of any desired thickness, which is formed of a rectangular portion or arm, B, provided with two very much shorter but similarly-shaped arms, C D. These parts are so arranged with respect to each other that their central longitudinal axes emanate from a central point—the bolt-hole a—at angles of one hundred and twenty degrees, as shown. By this arrangement the perimeter of the tripod is formed with three V-shaped openings, while upon the sides of said tripod-top are disposed a series of holes, 1 1, 2 2, 3 3, 4 4, arranged in pairs and adapted to receive the bifurcated ends of the tripod-legs. It is evident, with this shape of tripod-top provided with the extension B, that the rear part of the camera-box, when extended, has a firm support. Moreover, the entire apparatus is better balanced, and consequently there is less liability to vibrate. The bolt-hole a, to contain the bolt whereby the camera-box is secured to the tripod, is placed in the top A, coincident with the center of a circle which would circumscribe the arms C D; while the legs are to be removably secured to the tripod-top in the holes 1 1, 2 2, 3 3, 4 4, straddling the arms to which they are attached; hence when the apparatus is in position for work, with the bellows extended and the plate-holder in position, all the weight is along the longitudinal axis of the arm B, which is firmly upheld by the tripod-leg secured thereto by the holes 4 4. A series of holes, 4' 4', may be disposed as shown, and thus the position of the leg attached to it may be changed to suit circumstances at any point along the arm B. Furthermore, I have provided the holes 3 3, which thus enable me to arrange all the tripod-legs at equal distances from the bolt-hole a, after the usual manner of disposing them, while the arm B, by its superior length, still affords additional security to the rear and extensible part of the camera-box and renders it much more steady, since the strain through the bolt-hole a is very much diminished.

The changes in the positions of the leg co-

operating with the long arm B are sufficient to enable the operator to use the same tripod for varying sizes of camera-boxes. Thus for a small size the legs may be secured as usual; 5 but in the event of a large box with a long-focused lens being employed, the leg, now secured—say at 3 3—is shifted outwardly to the holes 4 4 or 4' 4', as may be desired; hence it is evident that this tripod combines all the 10 good points of the ordinary tripod, with the increased advantages that for outdoor work in windy weather, or at any desired moment when increased steadiness is wanted, it can easily and readily be obtained.

15 I am aware that it is not new to provide a tripod-top with three devices for attaching the legs, the relative positions of these devices corresponding to those of the three arms of my tripod-top. This construction I do not claim; 20 but

I claim--

1. In a tripod, the combination, with the

tripod-legs removably attached to the tripod-top, of a tripod-top formed with two short arms, C D, and a long arm, B, the rear tripod-leg co-operating with the latter, being adjustable toward or away from the central bolt-hole, a, substantially as and for the purposes herein stated. 25

2. The combination, with a tripod-top to 30 which are removably secured tripod-legs, of a leg adjustable toward or away from the bolt which secures the camera-box, substantially as described.

3. A tripod-top, A, formed of the arms B C 35 D, provided with the bolt-hole a, and laterally pierced at 1 1, 2 2, 3 3, 4 4, by which to secure the legs upon which it is mounted, as set forth.

In testimony whereof I affix my signature in presence of two witnesses.

THOMAS H. BLAIR.
